United States Patent Office

Des. 211,273
Patented June 4, 1968

211,273

KETTLE

Frederick S. Waller, Caledon, Ontario, Canada, and John E. Reed, Glen Ellyn, Ill., assignors to Sunbeam Corporation, Chicago, Ill., a corporation of Illinois

Filed Nov. 3, 1967, Ser. No. 9,266

Term of patent 14 years

(Cl. D44—25)

FIG. 1 is a perspective view of a kettle embodying our new design;

FIG. 2 is a top plan view thereof;

FIG. 3 is a side elevational view thereof;

FIG. 4 is a front elevational view thereof; and

FIG. 5 is a rear elevational view thereof.

We claim:

The ornamental design for a kettle, as shown.
